Ludwig, PLLC

(57) **CLAIM**

The ornamental design for a coaster, as shown and
described.

DESCRIPTION

FIG. 1 is a top front perspective view of a coaster, showing
my new design;

FIG. 2 is a front elevation view thereof, with the rear
elevation view being a mirror Image thereof;

FIG. 3 is a right side elevation view thereof, with the left side
elevation view being a mirror Image thereof;

FIG. 4 is a top plan view thereof;

FIG. 5 is a bottom plan view thereof;

FIG. 6 is an exploded view thereof; and,

FIG. 7 is a section view thereof, taken along line 7-7 from
FIG. 4, shown in an enlarged scale.

The broken lines shown in the drawings illustrate portions of
the coaster that form no part of the claimed design.

1 Claim, 4 Drawing Sheets
